UNITED STATES PATENT OFFICE

FREDERICK S. McCULLOUGH, OF EDGEWOOD, PENNSYLVANIA

HOT CATHODE DEVICE

Application filed January 5, 1926. Serial No. 79,352.

This invention relates to hot cathode devices, and more particularly to devices of this kind wherein the cathode is indirectly heated by means of a separate heating element associated therewith in such manner as to deliver heat thereto.

In certain types of hot cathode devices it has heretofore been proposed to form the cathode in the form of a shell and to have a heating wire within the shell. This heating wire has either been supported within the shell by a suitable supporting means, or has been embedded within a mass of porcelain or other heat resistant material, the shell forming the cathode being fitted about this mass of porcelain.

The present invention relates particularly to an improvement in such devices, and has for its object to provide a construction where 20 in one end of the heating element is connected directly to the cathode element to materially simplify the construction of the tube and to increase its efficiency. The present invention pertains more especially to rectifier 25 tubes of the two electrode type wherein it is desired to have a large emitting cathode with a relatively small heating element, and wherein in the cathode is non-equi-potential.

The invention may be readily understood 30 by reference to the accompanying drawing, which illustrates diagrammatically one form of the present invention. In the drawing the figure represents a vertical section through the electrodes of a two electrode cathode de- 35 vice with the envelope thereof illustrated by a dotted outline.

In the drawing the dotted outline designates a suitably constructed envelope, preferably of glass, which is evacuated. Support- 40 ed within the envelope 2 are two electrodes, one of which is the plate or anode 3, and the other of which is the cathode 4. The cathode 4 is in the form of a shell or cylinder 5 of sheet metal within which is a suitable heating wire 6. The shell 5 may, if desired, have a coating of a suitable character for increasing its electron emissivity.

One end of the heating wire 6 is directly connected at 7 to the shell 5. The other end 50 of the heating wire 6 connects with a lead-in

wire 8. The shell 5 is connected to and supported by a second lead-in wire 9 whose point of attachment to the cathode is preferably at the end opposite the point where the heater wire connects to the cathode, while 55 a third lead-in wire 10 is attached to the plate 3.

In operation a source of alternating current may be connected across the lead-in wires 8 and 9. The current flowing through the heating wire 6 will serve to heat the shell 5 to a point where it will sustain electron emission to effect the operation of the tube.

The arrangement herein provided has several advantages. In the first place, there 60 need be only three lead-in pins or connections at the base of the tube. By reason of the fact that one end of the heating wire is connected directly to the cathode instead of to another lead-in wire or post, as has heretofore been 65 the practice, heat which would otherwise be conducted into the base is carried directly to the cathode.

A further advantage of the construction resides in the fact that the tube can be assembled much more easily and rapidly by connecting the end of the heater wire directly to the cathode instead of to an external pin or post. It will be seen that the cathode is in 70 series with the heater wire, preferably its 75 entire length being in series, so that there is a current flow therealong during the operation of the tube.

I claim:

An electron tube having a tubular cathode member, a heater wire having a loop inside the cathode member and extending longitudinally of said cathode tube, both ends of said wire being at the same end of the cathode, one end of said wire being connected to 80 one end of the cathode, a heater current supply wire connected to the other end of the heater wire, and a second current supply wire connected to the cathode only at that end 85 of the cathode opposite the end to which the heater wire is connected thereto.

In testimony whereof I have hereunto set my hand.

FREDERICK S. McCULLOUGH.
